RESISTOR TERMINAL

Max G. Bales, Anderson, Ind., assignor to General
Motors Corporation, Detroit, Mich., a corpora-
tion of Delaware

Application January 4, 1952, Serial No. 265,013

3 Claims. (Cl. 201—67)

1

This invention relates to an improved resistor terminal of the kind used in an ignition system for internal combustion engines.

Resistors for use in the primary circuit of the distributor when used with an ignition coil requiring a current limiting resistor should be built into the primary terminal of the distributor and the resistance should be completely enclosed so that it would be difficult to operate the circuit. Should the resistance unit be a separate item or a part of the ignition coil it is possible to wire around it in such a manner that excessive current would result in the primary circuit and damage the distributor points or the coil.

An aim of the present invention is to provide an improved heavy duty resistor combined with a distributor terminal to form a unitary structure which is mounted in an opening provided in a distributor housing.

Further objects and advantages of the present invention will be apparent from the following description reference being made to the accompanying drawings wherein a preferred embodiment of the present invention is clearly shown.

In the drawing:

Fig. 1 is a wiring diagram illustrating the use of the present invention.

Fig. 2 is a sectional view, on an enlarged scale, taken on line 2—2 of Fig. 1.

Fig. 3 is a sectional view taken on line 3—3 of Fig. 2.

Fig. 4 is a sectional view taken on line 4—4 of Fig. 2, but on a larger scale.

Referring to Fig. 1 a combined primary terminal and resistance unit 20 embodying the present invention is shown in an ignition circuit for an internal combustion engine, 21 designates a battery or other source of current grounded at 22 and connected by a wire 23 to an ignition switch including stationary contacts 24 and 26 and a movable contact 25. The contact 25 is connected by a wire 27 to one end of the primary winding 28 of an ignition coil 30. One end of the secondary winding 29 of the ignition coil is connected to the primary winding while the other end is connected by a wire 31 to the high tension terminal 32 of an ignition distributor 33. The other end of the primary coil 28 is connected by a wire 34 to a terminal 35 of the unit 20. The terminal 35 is connected to a terminal 36 through a resistance element 37. Terminal 36 is connected to a leaf spring 38 of a circuit breaker lever 39 carrying a contact 40 cooperating with a stationary contact 41 grounded at 42. The lever 39 includes a rub-

2

bing block 43 of insulating material operated by a cam 44.

Referring to Fig. 1, the unit 20 includes a heat conducting metal case or housing 45 having an end wall 46 formed with an aperture to receive a reduced end 47 of a heat conducting metal bushing or member 48 which is riveted over the inside of the end 46. A body 49 of insulating material is so shaped as to have an annular flange or collar 50, a reduced section 51, and an annular flange or collar 52. The collar is formed with a recess 53 to house the riveted over portion of the bushing 48. The terminal 33 is a conducting bolt and passes through body 49, by way of a bore 55. The bolt is provided with a head 56 which is adapted to seat in a recess 57 in the body 49. The shank of the bolt may be provided with a portion 58 that is shaped to prevent turning of the bolt 36 relative to the body 49 due to jarring and vibrations.

The shank of the bolt 36 passes through an insulating bushing 59 housed within the coupling 48. The end of the bushing 48 provides a shoulder 60 against which rests an insulating washer 61. A nut 62 threadedly engaging the threaded end of the bolt, when threaded home, draws the collar 52 tightly against the end wall 46.

To prevent the body 49 from turning within, the housing 45, due to jarring and vibrations, the collar 52 is provided with a notch 65 in which is received a detent or depression 66 formed in the housing 45. The body 49 is formed with a slit 67 which communicates with the recess or pocket 57. Between the collars 50 and 52 the portion 51 is formed with a spiral groove 68 to receive the resistance element 37 having one end 37a extending through the slit 67 and into the recess 57 and is fixed to the bolt head 56 in any suitable manner, for example, by soldering. As to the specific formation of the head of the bolt as shown, in Fig. 4, the head may be formed with a boss 69 having a slot 70 to receive the end 37a of the resistance element 37 and portions of the boss may be staked over the end 37a. If desired, solder 45 may be used to hold the end within the confines of the slot 70. The other end 71 of resistance element 37 is threaded through an angular bore 72 in the terminal 35 carried, as shown in Fig. 2 by a closure or disc 73 of insulating material.

A resilient sheet metal washer 75 is placed adjacent the collar 50. The central aperture of washer 75 is of sufficient size so that it will not engage the riveted over portion 76 of the terminal 35 when the washer engages the collar 50 and the closure 73 is in its complete assembled

position. Thus the washer is insulated from the terminal 35.

The closure 73 is secured within the housing by spinning or turning over the housing as at 11. When the closure 73 is in its complete assembled position the resisting force of the washer 75 will maintain the body 49 firmly against the end wall 46. When the closure 73 is secured within the housing the terminal end 71 of the resistance element is secured to the terminal as by soldering 10 or sweating as indicated at 78.

In this construction there is provided a terminal and resistance element unit adapted for use with an electrical apparatus, for example, an ignition timer, which is simple in design, economical in manufacture and efficient in operation. This construction makes for compactness and durability and the resistance element is resiliently supported within the housing 45 and negatives any separation or breaking of connections between the terminals 35 and 36 and the element. 15

It will be noted that the reduced or intermediate portion 51 of the body 49 supports the resistance element 37 out of contact from the housing 45 and the coupling member 48, but the resistance element 37 is sufficiently close to the housing 45 so that the housing will absorb heat from the element 37 when hot, said housing 45 transferring some of the heat to the coupling member 48 which in turn transfers heat to a timer housing 80.

The terminal unit 20 is attached to the timer housing 80 by threading the bushing 48 in a tapped hole 81 provided by the housing in the manner shown in Fig. 2. The housing supports a head 82 for the ignition distributor 33.

While the embodiment of the present invention as herein disclosed, constitutes a preferred form, it is to be understood that other forms 40 might be adopted.

What is claimed is as follows:

1. A terminal assembly for use with an electrical apparatus having a metal housing, said assembly comprising the housing, a heat conducting casing adapted to be supported by the housing, said casing having a closure of insulating material at one end; a terminal carried by the closure; a sleeve of insulating material located within the casing and having an internal shoulder; a second terminal adapted to clamp the sleeve against an internal wall of the casing, said terminal having a head adapted to engage the shoulder, a shank portion extending into the housing and having a threaded portion and a nut 45 threadedly engaging the shank whereby the tightening of the nut clamps the sleeve against the casing; means for insulating the second terminal and the nut from the casing; a resistance element carried by the sleeve; and means for establishing electrical contact between said resist- 50

5 ance element and said terminals, said resistance element having its intermediate portion sufficiently close to the casing whereby the casing will be effective for absorbing heat emanating from the resistance element when hot.

2. A terminal assembly for use with an electrical apparatus having a metal housing, said assembly comprising the housing, a heat conducting casing adapted to be supported by the housing, said casing having a closure of insulating material at one end; a terminal carried by the closure; a sleeve of insulating material located within the casing and having an internal shoulder and having grooves formed in the exterior surface thereof; a second terminal adapted to clamp the sleeve against an internal wall of the casing, said terminal having a head adapted to engage the shoulder, a shank portion extending into the housing and having a threaded portion, and a nut threadedly engaging the shank whereby the tightening of the nut clamps the sleeve against the casing; means for insulating the second terminal and the nut from the casing; a resistance element carried by the sleeve; a resistance element wound in said grooves and having its opposite ends passed through a slot in said sleeve to the interior of said sleeve; and means for establishing electrical connection between said ends of the resistance element and said terminals. 25

3. A terminal assembly for electrical apparatus having a metal housing provided with an opening, said assembly comprising the housing; a heat conducting casing having a tubular extension at the other end, said extension having to have threaded engagement with the opening of the housing; a body of insulating material located within the casing and having a counter-bored passage therein to provide a shoulder; a terminal member adapted to clamp the body against an interior wall of the casing, said terminal member having a head adapted to engage the shoulder within the passage of the body, a shank portion projecting through the extension and having a threaded portion, and a nut threadedly engaging the threaded shank whereby tightening of the nut clamps the body to the casing; means for insulating the shank and nut from the extension; a second terminal member carried by the closure; and a resistance supported on the body and having electrical connection with each of said terminal members. 30
